ROBERT WILLIAM LEEMING, OF BRANTFORD, CANADA.

DEVICE FOR LAUNCHING LIFE-BOATS.

1,140,046.

Specification of Letters Patent.

Patented May 18, 1915.

Application filed July 7, 1914. Serial No. 849,480.

To all whom it may concern:

Be it known that I, ROBERT W. LEEMING, a subject of the King of Great Britain, and a resident of Brantford, in the Dominion of Canada, have invented a new and useful Improvement in Devices for Launching Life-Boats, of which the following is a specification.

My invention is an improvement in devices for launching life boats, and has for its object to provide a device of the character specified, adapted for launching life boats especially, from ships, other vessels, piers, or the like, wherein davits are provided for supporting the life boat connected to the vessel or pier in such manner that they may be rotated on a vertical axis to swing the boat from on board to a position above the water, and may then be swung out to lower the boat into the water.

In the drawings:—Figure 1 is a top plan view of the improved launching device supporting a life boat, Fig. 2 is a side view of the same, Fig. 3 is an enlarged section on the line 3—3 of Fig. 2, looking in the direction of the arrows adjacent to the line, Figs. 4, 5 and 6 are sections on the lines 4—4, 5—5 and 6—6, respectively, of Fig. 3, Fig. 7 is a side view of a portion of one of the davits, Fig. 8 is a longitudinal vertical section of a portion of the life boat, showing its connection with the launching apparatus, Figs. 9 and 10 are perspective views of modified constructions, Fig. 11 is a partial section of the embodiment shown in Fig. 10, and Fig. 12 is a perspective view of the device in use.

The embodiment of the invention shown in Figs. 1 to 7 inclusive, is shown in connection with a vessel or pier 1, and a boat 2, which is being launched from the vessel or pier 1. The launching device comprises a pair of davits of similar construction, each comprising an upright or column 3 in the form of a channel bar, and hinged to the outer face of the side wall of the vessel or pier, by means of a bracket plate 4. The bracket plates are bolted or otherwise secured to the vessel as indicated at 5, and each plate is provided with a pair of parallel laterally spaced bearing lugs 6, between which the lower end of the channel bar is received, and a pivot pin 7 is passed through registering openings in the lugs, and through openings in the lower ends of the side walls of the channel bar, and each pin

is engaged by a cotter pin 8 or the like, to prevent disengagement thereof. The uprights are thus mounted to swing outwardly from the vessel or pier if desired, and the davits of each pair are connected by means of a link 9. A double eye bolt 10 is passed transversely of each upright, intermediate the ends thereof, and with the eyes 11 on the outer faces of the side walls of the upright. The link 9 is provided with an eye at each end which engages the innermost eye of the adjacent bolt, and sectional links are connected with the outermost eyes of the bolt.

Each of the sectional links consists of a section 12 and a section 12^a, the adjacent end of the sections being threaded and being engaged by a double nut 13. The ends of the nuts are oppositely threaded, as are also the adjacent ends of the sections, and the sections and nuts form turn buckles for permitting the effective length of the links 12—12^a to be varied. Each of the links 12—12^a extends outwardly and downwardly, and the section 12^a of each link is provided with an eye at its outer end, which engages an eye 14 on the plate 15, secured to the side wall of the vessel or pier. The davits are thus braced against lateral movement in either direction, the arrangement being such that they must swing vertically in parallel planes and without lateral movement.

It will be noticed from an inspection of Fig. 2 that the eyes 14 of the plates 15 and the pivot pins 7, are in horizontal alinement, so that there is no shortening of the distance between the eye bolt 14 and the adjacent eye bolt 11, during the swinging movement of the davits. At its upper end each channel bar 3 is reinforced and braced by a T shaped plate, consisting of a body 16 and a central rib 17. The body 16 of each T plate is of sufficient width to extend beyond the outer faces of the side walls of the channel bar 3, and the said extended edges are provided with openings for receiving bolts 18, the bolts extending transversely of the outer faces of the side walls of the channel bars for a purpose to be presently described.

Near the upper end of each channel bar a guide tube or shaft 19 is arranged, each tube fitting between the side walls of the channel bar, and each of the guide tubes 19 is provided near its lower end with an external annular groove 20, for receiving a substantially U-shaped holding bracket 21,

the said bracket fitting the groove at the front and sides of the guide tube, and filling the space between the side walls of the channel bar and the tube as shown more particularly in Fig. 4. The body of each of the said brackets is provided with laterally extending perforated lugs 22, which register with the openings for the bolts 18 in the body of the T plate, and the said bolts pass through the perforations of the lugs and are engaged by nuts 23, on the outer face of the bracket.

A laterally extending arm 24 is connected with the upper end of each of the tubular guide tubes 19, each arm having a hub or bearing sleeve 25, fitting the upper end of the tubular guide tube, and resting at its lower end against the upper end of the upright 3, the T plate 16-17, and a clamping bracket 26, which clamps the tube to the upright at the upper end thereof. The guide tube 19 is extended above the upper end of the upright to receive the hub 25 and to extend to a position flush with the upper end of the said hub.

A pulley 27 is journaled in a substantially U-shaped bracket 28, at the upper end of the bore of the guide tube 19, and the arms of the bracket 28 are integral with a plate 29, which is secured to the upper face of the arm 24, by means of screw bolts 30 or the like. Another pulley 31 is connected to a similar U-shaped bracket 32, at the outer end of the arm, and the arms of the bracket are integral with a similar plate 33, which is secured to the upper face of the arm near its outer end, by means of screw bolts 34 or the like.

A flexible member 38, as for instance, a rope, wire or cable, passes over the pulleys 27 and 31 from a davit hook 36, downwardly through the bore of the guide tube 19, and at the lower end of the said bore, beneath a pulley 37, journaled on a journal pin 39, held in bearings 40, arranged transversely of the channel of the upright 3, near the upper face of the deck of the boat or pier 1 and then over a roller 41, journaled on the deck to reeling or winding mechanism to be later described. The pulley 42 of one davit is held in a substantially U-shaped bracket 43, which is connected to straps 44, secured to the deck or pier. The pulley 42^a is journaled between plates 45 and 45^a, secured to the deck in spaced relation adjacent to the other davits.

The reeling or winding mechanism comprises a reel 46 which is provided with two sections or divisions and the respective flexible members 38 wind upon the said divisions or sections in the same direction. The reel is journaled in bearing brackets 47 on the deck, and a worm wheel 48 is secured to the reel at one end between the reel and the adjacent bearing 47. The worm wheel is

engaged by a worm 49 on a shaft 50, journaled transversely of the reel at the worm wheel and provided at its ends with cranks 51, for convenience in rotating the reel.

Between the lower end of the guide tube 19 and the pulley 37 a brake is arranged, the said brake comprising oppositely arranged blocks 52 and 52^a, each grooved on its inner face to receive the flexible member 38. The block 52 rests between the side walls of the channel bar, fitting the same as shown in Fig. 5, and the block 52^a fits against the outer face of the said block. The block 52 is provided with transverse openings for permitting the passage of threaded stems 53 from the block 52, and the block 52^a has longitudinally extending perforated lugs 54, for receiving the bolts 18 before mentioned, which engage the extended edges of the T plate 16-17. The threaded stems 53 also extend through openings in lugs 55 at the ends of a nut 56, and nuts 57 are threaded on to the stems on the opposite side of the lugs from the blocks 52-52^a. The nut 56 is thus held from outward movement with respect to the blocks 52 and 52^a, and a threaded stem 58 is rotatably connected with the block 52^a at its center, and the stem extends through the nut and is provided with a wheel 59, for convenience in rotating the same.

It will be evident that when the hand wheel is turned, the block 52 will be moved toward or from the block 52^a to compress or release the flexible member. The movement of the flexible members may be thus nicely controlled by means of the hand wheels 59 to permit the life boat to move slow or fast, or to stop the same at any point desired.

The plate 40 that supports the journal pin 39 of the pulley 37 is as before stated, connected to the davit. The connection is made by means of the bolts 18, before mentioned, the said bolts being passed through the extended side edges of the body 16 of the T plate and through openings in the side edges of the plate 40, and the nuts 23 clamp the plate to the upright. This plate is near the level of the deck, and the plate 45^a before mentioned, that supports the pulley 42^a, is secured to the deck just below the pulley 37. The plate 45^a supports the roller 41, and mechanism is provided in connection with this plate for clamping the adjacent davit permanently in upright position. The said mechanism comprises a flexible member 60, a chain in the present instance, having one end connected to a fixed stop 117, an eye in the present instance, on the plate 45^a and at one side of the davit. The other end of the chain has a hook 118, which is adapted to engage the eye of an eye bolt 119, and the threaded portion of the bolt passes through lugs 120 on the plate 45^a at the

opposite side of the davit from the eye 117, and through a nut 121, arranged between the lugs and journaled in the same. The nut is provided with a hand wheel 122, for convenience in turning the same, and it will be obvious that when the nut is turned in the proper direction the chain will be tightened around the davit to hold it in upright position. By turning the nut in the opposite direction, the eye bolt may be loosened to permit the davit to swing away from the deck or pier.

The hooks 36 before mentioned, at the outer ends of the flexible members 38 are adapted to engage latch pins 61, for connecting the hooks with the boat 2, before mentioned. Each of the latch pins is provided with a fork at one end, and the arms 62 of the fork engage opposite faces of one end of a lever 63, intermediate the ends of the lever, and a pin 64 is passed through the arms and the lever to connect the latch pin to the lever. The lever is pivoted at one end to the decking 65 at the adjacent end of the boat, as indicated at 66, and a coil spring 67 is arranged between the lever and the decking, the spring acting normally to move the lever in a direction to cause the latch pin to engage the hook 39. A connecting bar 68 is pivotally connected to the bottom of the boat by means of bracket plates 69, the said plates having bearing lugs 70, between which the lower end of the bar is received.

35. A pivot pin 71 is passed through the lugs and through a bearing at the end of the bar, and a cotter pin 72 is passed through the end of the pin to prevent disengagement thereof. The upper end of the bar 68 passes 40 through an opening 73 in the decking of the boat and above the decking the bar is forked. The arms 74 of the fork are adapted to fit opposite sides of the hook 36, and the said arms have registering openings through 45 which the latch pin 61 may pass to pivotally connect the hook to the arms 74 of the bar.

A wheel 75 is journaled on a journal pin 76, extending laterally from that side of the boat adjacent to the vessel, and the said wheel is provided with a pair of grooves on its peripheral surface, the grooves lying alongside each other. Flexible members 77 are connected at one end to the respective grooves, and the said members extend in op-

55. The said members extend in opposite directions, being connected at their opposite ends to the free ends of the levers 63 before mentioned. The flexible members pass through guide tubes 78 held on the side of the boat by bearing clips 79, and a socket 80 is secured to the wheel extending radially of the outer face thereof. The socket is adapted to be engaged by a handle 81, and it will be evident that when the wheel is turned by means of the handle in the proper 65 direction, the free ends of the levers 63 will

the lever 64, the free ends of the levers 63 will be moved, after which a lever 65 will be moved and the second bracket of the main frame 61

be moved toward each other to withdraw the latch pins from the openings of the arms 74. The arms 74 are then moved into the position shown in Figure 10.

The operation of the launching mechanism just described, is as follows:—The life boats are supported on cradle blocks on the deck and to launch a boat, the davits are swung inward and the hooks are attached to the boat by means of the cable, 70

to the boat by means of the latch pins 61. The reel is now turned in a direction to lift the boat clear of the cradle blocks, and it is then lowered to the deck.

is then swung outward in the position shown in Fig. 1. The passengers and crew may now take their places in the boat. If the

the sea is perfectly smooth the boat may be lowered down the side of the vessel, the davits holding the position shown in Figs.

gavits holding the position shown in Figs. 1, 2 and 3 until the boat strikes the surface of the water. Should however, there be a sea running or should the vessel have a

a sea running or should the vessel have a list in-board, with the boat in the position of Figs. 1 and 3, the wheels 59 are turned to clamp the cable 22 to the deck.

to clamp the cables 38 between the plates 52 and 52^a, and after the cables have been clamped and the deck chain released the reel

is operated to unreel the cables. The boat 90 will hold the position indicated in dotted lines in Fig. 3, but the davits as a whole

lines in Fig. 3, but the davits as a whole, will swing outward from the side of the vessel until the boat strikes the surface of the water away from the side of the vessel. In

water away from the side of the vessel. In the first case when the boat strikes the water, the proper person will swing the wheel 73 by means of the handle 51 in the direction

by means of the handle 81 in a direction to cause the free ends of the levers 63 to move toward each other, thus releasing the latch 100.

100
pins from the davit hooks, and the davits may be returned to their original position, by running the reel in the opposite direc-

... running the reef in the opposite direction. In the latter case, the person in charge of the life boat during the lowering operation is ready with the releasing mechanism.

is ready with the releasing mechanism and as soon as the boat is solely or partially water borne, on the top of a wave or swell, it operates the mechanism.

He operates the wheel to simultaneously withdraw the latch pins and the boat is launched free and clear of all lines and of 110

the ship. The moment that a boat is released from the davit hooks, the reel or winch is operated to return the davits to

it will be evident that any preferred form of motor might be connected to the wind-

With the hand operated winch, the time required to haul up the boat is

required to launch a boat and return the device to original position is short, and with motor this time would be shortened still further. 120

urther. It will be evident that the improved device meets the requirements of the International Conference Report, which 125

International Conference Report, which 125
calls for a launching device capable of
launching a boat on either side of a vessel
with a 15% list.

It will be readily seen by reference to fig. 3 that the weight of the boat will swing 130

the davits, even with a 15% list, through the action of gravity. In fact gravity alone will swing the davits at a much greater list than 15%. It will be evident that the center of the boat must be inside the pivot pin 7 before the device will not be swung by gravity.

In use, the columns or uprights need not be more than 20 feet in length. Even in 10 the largest boats the columns or uprights 3 need not be of excessive length. For instance with a boat having a boat deck 60 feet above the water line, a 20 foot column 15 or upright will operate nicely. The life boats must however, be lowered with respect to the columns before permitting the columns to swing outward. In a vessel under 20 the above conditions the life boat after loading in the position in Fig. 3 would be lowered say, 30 or 40 feet, or to a point where when the columns would swing outwardly the boat would touch the water. This point could be marked on the cables as a guide.

After the life boat has been lowered with 25 respect to the columns as above mentioned to the proper point, the wheels 52 would be tightened to clamp the cables and the deck chain released, after which the winch would be operated to permit the boat to swing 30 them outward. It will be evident that any desired form of releasing mechanism for releasing the boat from the davit hooks might be used but the form shown is a convenient form, by means of which the boat 35 is supported without any danger of breakage or pulling loose, and at the same time the davit hooks may be easily released and simultaneously.

In the modified form shown in Fig. 10 40 the column or upright 3^a is similar to the column or upright shown in Figs. 1 to 5, being a channel bar and having the openings at its bottom for permitting it to be hinged to the side of the vessel in the same manner as the column 3 is hinged in Fig. 3. The columns 3^a are mounted on the vessel in precisely the same manner as the columns 3, and are braced and connected to each other and to the vessel by means of 50 the double eye bolts 11, the links 10 and the links 82 corresponding to the sectional links 12-12^a. The side walls of the channel bar are connected at their upper ends by an integral web 83, and the column is provided 55 with a frusto-conical extension 84 from the web. At each end of the extension cylindrical bearing surfaces 85 and 86 are provided. An arm 87 is provided with a bearing 88 for engaging the portion 85 and the 60 outer end of the arm is formed into an eye 89. A collar 90 encircles the bearing surface above the bearing 88 and a set screw 91 is threaded through the collar into engagement with the bearing surface to prevent 65 upward movement of the arm. An inclined

brace 92 is connected at one end to the outer end of the arm 87 as indicated at 93, and the upper end of the brace is provided with a bearing 94 which encircles the bearing surface 96. Collars 95 are arranged above 70 and below the bearing 94, and set screws 96 are threaded through the collars into engagement with the bearing surface. A hanger 97 is connected with the eye, and a pulley 98 corresponding to the pulley 31 75 of Figs. 1 to 3 is journaled in the hanger. The operation of the above construction is precisely the same as that shown in Figs. 1 to 3.

The superiority of the arrangement of 80 cable and which is so marked that the said arrangement may with advantage be applied to the ordinary davit now in use. In Fig. 9 is shown the manner of applying the said arrangement to the ordinary davit. 85 The davit 99 having the lateral arm 100 at its upper end provided with the eye 101 for engagement by the hanger 102 in which the pulley 103 is journaled, is rotatably mounted in upper and lower bearings 104-105, 90 respectively, for rotation on a vertical axis. The bearing 104 is provided with a pair of laterally spaced bearing lugs 106, and a pulley 107 corresponding to the pulley 41 of Fig. 1, is journaled between the lugs. 95

A pulley 108 is connected to the deck of the vessel 109, by means of bearing plates 110, the said pulley corresponding in position and arrangement to the pulley 42, before mentioned. A fourth pulley 111 is 100 journaled in a hanger 112, which is connected to a ring 113, which encircles the davit at the junction of the arm 100 with the body, and a holding plate 114 is secured to the davit at this point to prevent movement of the ring longitudinally of the davit. 105

The pulleys 103-107-108 and 111 support a flexible member 115, a rope or cable which passes from the winch shown in Fig. 1, and the outer end of the cable is provided with the usual davit hook 116. With this construction, the life boat is picked up off the cradle blocks by means of the winch, and it is then swung outward as above described and lowered to the water. The davits are not mounted to swing outwardly but the operation is otherwise the same as in the first-described construction. 115

I claim:-

1. A pair of davits, each of the said davits 120 comprising a column or upright of channel shape, an arm rotatably connected with the upper end of the column or upright to revolve around the upright, a bracket adapted to be secured to a fixed support at each 125 davit, a hinge connection between each column and the adjacent bracket for permitting the upper end of the column to swing outwardly and downwardly, said column being adapted to extend above the boat deck 130.

of a vessel, a pulley journaled at the outer end of each arm, a pulley journaled on the arm near the top of each column, a pulley journaled on each column intermediate the ends thereof, a flexible member passing over the pulleys and having a davit hook at its outer end for engaging a boat to support the same, and brake mechanism in connection with each column for preventing movement of the flexible member, said mechanism being arranged on the column between the last-named pulleys and comprising a pair of blocks having registering grooves for receiving the flexible member, the blocks being connected to the column and being movable laterally with respect to each other, and means for clamping the outer block on the inner block.

2. A pair of davits, each of the said davits comprising a column or upright of channel shape, an arm rotatably connected with the upper end of the column or upright to revolve around the upright, a bracket for each davit adapted to be secured to a fixed support, a hinge connection between each column and the adjacent bracket for permitting the upper end of the column to swing outwardly and downwardly, said column being adapted to extend above the boat deck of a vessel, a pulley journaled on the arm near the outer end of each arm, a pulley journaled at the top of each column, a pulley journaled on each column intermediate the ends of the column, a flexible member passing over the pulleys and having a davit hook at its outer end for engaging a boat to support the same, and brake mechanism in connection with each column for preventing movement of the flexible member, said mechanism being arranged between the last-named pulleys.

3. A pair of davits, each of the said davits comprising a column or upright of channel shape, an arm rotatably connected with the upper end of the column or upright to revolve around the upright, a bracket adapted to be secured to the side of a vessel at each davit, a hinge connection between each column and the adjacent bracket for permitting the upper end of the column to swing outwardly and downwardly, said column being adapted to extend above the boat deck of a vessel, a pulley journaled at the outer end of each arm, a pulley journaled on the arm near the top of each column, a pulley journaled on each column near the intermediate ends of the column, a flexible member passing over the pulleys and having a davit hook at its outer end for engaging a boat to support the same, and brake mechanism in connection with each column for preventing movement of the flexible member.

4. In combination with a vessel, a pair of davits, each davit consisting of a column

hinged to the side of the vessel at the lower end of the davit and with the davit extending above the deck from which the boats are to be lowered, an arm rotatably connected with the upper end of each column for swinging movement around the column, a flexible member in connection with each davit for connection with the boat at one end to support the same, a common means for simultaneously moving the flexible members of both davits in the same direction, direction elements for the flexible members, one of the said elements being at the outer end of the arm, another of the said elements being near the top of the column, the other direction element being on the column near the level of the deck from which the boats are to be launched, and means on the column between the last-named elements for clamping the flexible member to the column, each of the said clamping mechanisms consisting of a pair of superposed blocks having co-operating grooves for receiving the flexible members, means for forcing the blocks toward the column, and means for bracing the davits against each other and against the vessel to prevent lateral movement of the davits.

5. In combination with a vessel, a pair of davits, each davit consisting of a column hinged to the side of the vessel at the lower end of the davit and with the davit extending above the deck from which the boats are to be lowered, an arm rotatably connected with the upper end of each column for swinging movement around the column, a flexible member in connection with each davit for connection with the boat at one end to support the same, a common means for simultaneously moving the flexible members of both davits in the same direction, direction elements for the flexible members, one of the said elements being at the outer end of the arm, another of the elements being on the arm adjacent to the column, the other direction element being on the column at the level of the deck from which the boats are to be launched, and means on the column between the last-named elements for clamping the flexible member to the column.

6. Davits for launching boats from vessels, said davits being arranged in pairs, and each davit comprising a column adapted to be hinged to the vessel below the level of the deck from which the boats are to be launched and adapted to extend above the level of the deck, an arm mounted to rotate on each column at the upper end thereof, a flexible member having a hook at its outer end for engaging the boat, and a common means on the deck for simultaneously moving the cables of the pair of davits in the same direction, and direction elements for supporting and guiding each cable, one of the said elements being connected to the

column near the level of the upper surface of the deck, and means on the column adjacent to the said direction element for clamping the cable to the column.

5 7. A pair of davits, each davit comprising a column adapted to be hinged to the side of the vessel and adapted to extend above the boat deck, a bolt arranged transversely of each column and having eyes at each of its 10 ends, a link connecting the adjacent eyes of the columns, a link connecting the outermost eye of each column to the deck, each of the last-named links being sectional, and a turn-buckle in connection with the sections, 15 the connection with the vessel being in horizontal alignment with the hinge connection of the columns, an arm journaled on the upper end of each column for rotating movement around the column, flexible members 20 having hooks at their outer ends, the other ends of the flexible members being adapted for connection with a winch or the like, and direction elements in connection with the davits for guiding and supporting 25 the members, one of the said elements being at the outer end of the arm, another being on the arm adjacent to the column, and another being near the level of the deck, and means for clamping each flexible member to the column adjacent to the last-named direction element.

30 8. A pair of davits, each davit comprising a column adapted to be hinged to the side of the vessel and adapted to extend above the boat deck, an arm journaled on the upper end of each column for rotating movement around the column, flexible members 35 having hooks at their outer ends, the other ends of the flexible members being adapted for connection with a winch or the like, and direction elements in connection with the davits for guiding and supporting the members, one of the said elements being at the outer end of the arm, another being on the 40 arm adjacent to the column, and another being near the level of the deck, means for clamping each flexible member to the column adjacent to the last-named direction element. releasable means for connecting each flexible member to the boat, and a common means for simultaneously releasing both flexible members from the boat.

45 9. Davits each comprising a column having an arm at its upper end journaled on the column for rotation about the column, a hinge connection between the lower end of each column and a fixed support for per-

mitting the column to swing outwardly on the connection, a cable in connection with each column, each cable having a hook at 60 its outer end, pulleys for supporting and guiding each cable, one of the pulleys being at the outer end of the arm, another adjacent to the top of the column and another intermediate the ends of the column, and 65 means for clamping each cable to the column between the last-named pulleys.

70 10. Davits each comprising a column having an arm at its upper end journaled on the column for rotation about the column, and each column having a tubular portion at its upper end opening through the axis of rotation of the arm for receiving a cable for connection with a boat, and having pulleys for supporting the cable at the outer end of 75 the arm and at the upper end of the opening, each column being hinged at its lower end for permitting the column to swing outwardly, each column extending above the boats to be launched, releasable means for 80 fixing each column in upright position, and a brake for the cable in connection with each column.

85 11. Davits each comprising a column having an arm at its upper end journaled on the column for rotation about the column, and each column having a tubular portion at its upper end opening through the axis of rotation of the arm for receiving a cable for 90 connection with a boat, and having pulleys for supporting the cable at the outer end of the arm and at the upper end of the opening, each column being hinged at its lower end for permitting the column to swing 95 outwardly, each column extending above the boats to be launched, and releasable means for fixing each column in upright position.

100 12. Davits each comprising a column having an arm at its upper end journaled on the column for rotation about the column, and each column having a tubular portion at its upper end opening through the axis of rotation of the arm for receiving a cable for connection with a boat, and having pulleys for supporting the cable at the outer end 105 of the arm and at the upper end of the opening, each column being hinged at its lower end for permitting the column to swing outwardly.
